Nelson M. Howard

UNITED STATES PATENT OFFICE

CLARENCE I. LANDER, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

METHOD OF LEVELING SHOES

Original application filed August 9, 1927, Serial No. 211,823. Divided and this application filed February 27, 1930. Serial No. 431,800.

This invention relates to the art of making shoes and is herein exemplified with special reference to its application to the leveling of shoes.

It is desirable in the manufacture of shoes, such as women's light and stylish shoes, made by welt and McKay methods in imitation of turn shoes, as well as in turn shoes themselves, to provide a close edge about the forepart and shank, that is, to bring the projecting portion of the sole in turn and McKay shoes, or the projecting portions of the inner sole, outer sole and welt in welt shoes into close relation to the upper. This is particularly important in welt shoes, in order that the outsole stitches may be hidden and is peculiarly difficult in welt work because of the bulky character of the inseam, that is, because of the inseam stitches and the stitch holding portions of the welt, upper and insole, in the trimming of which seam sufficient material must be left to afford adequate anchorage for the stitches.

In leveling the foreparts of shoes upon lasts of usual construction, the bottoms of which have a convexity or camber, the tendency of the leveling pressure is to force the material of the insole outwardly. This tendency causes not only loosening of the lasting tension of the upper but also is directly opposed to the formation of a close edge, since outward movement of the inseam, due to the leveling pressure thereon, tends to open the crease between the upper and the sole.

Moreover, the bulk of the inseam in proportion to the bottoming materials, particularly in light shoes, is such that the leveling pressure is taken mainly by the inseam and it is difficult to obtain sufficient pressure on the marginal portion of the shoe bottom to produce the desired shaping effects, including a close edge.

An object of this invention is to provide a method adapted for use in the leveling operation by which the above-described difficulties may be overcome.

To this end, the invention provides an improved method of leveling shoes, in which a marginal portion of a shoe sole is supported outside of the line of fastenings securing the sole to the upper while leveling pressure is ap-

plied to the bottom of said marginal portion of the sole without the application of any considerable amount of pressure to the fastenings securing the sole to the upper. As herein set forth, a last having the margin of its periphery inclined inwardly and toward the body of the last is utilized, pressure being applied progressively to the margin of the shoe bottom to force the inseam inwardly, thereby increasing the tension on the lasted upper and closing the crease between the upper and the outwardly projecting margin of the shoe bottom. It will be apparent that, when the pressure of a leveling instrument such as a roll is applied to the bottom of a shoe supported on the last, the leveling pressure is concentrated at the extreme edge of the last, which is the highest part of the margin of the last and supports the edge of the sole to withstand the opposed pressure of the leveling instrument when applied to the margin of the outsole which outwardly overhangs the edge of the last bottom. Furthermore, when the pressure of a leveling instrument such as a roll is applied perpendicularly to the general plane of the last bottom, the pressure tends to force the materials of the inseam inwardly of the shoe bottom because they are supported by the marginal surfaces of the grooves in the last bottom which incline inwardly of the shoe bottom because they are forcing of the inseam inwardly tends to tighten the lasted upper and to close the crease between the upper and the sole.

In the drawing,

Fig. 1 is a perspective view of a form of last employed in practicing the present invention;

Fig. 2 is a transverse section showing the forepart of a shoe made on the last of Fig. 1;

Fig. 3 is a transverse section through the shank of a shoe made on the last of Fig. 1; and

Fig. 4 is a transverse section through a shoe made on a last having at the shank the structure shown in the forepart of Fig. 1 and showing the operation of a leveling tool upon the shoe.

In the last illustrated in Fig. 1, which may be advantageously used in practising the

portion of this invention, the body portion 10 and the heel seat portion, including the heel plate 12, are of usual construction. The bottom of the forepart is formed with a shallow peripheral groove 14 extending around the forepart from the ball line to the ball line. This groove 14 extends to the extreme peripheral edge 13 of the last bottom and is of sufficient width to underlie the region of the inseam 18 of a shoe (FIG. 2), the central portion of the forepart being of usual formation having a transverse and longitudinal camber or convexity. The depth of the groove 14 is slight but sufficient to relieve the pressure of a leveling instrument on the inseam 18 and to concentrate the pressure at the peripheral edge 16 of the last bottom upon the edge or feather of the insole 20, the overlasted upper 22, the welt 24 and the margin of the outsole 26 to force them closely together and close the crease 28 between the upper and welt, or margin of the sole if the shoe has no welt. The formation of the groove 14 provides on the margin of the last bottom a surface 30 directed inwardly and toward the body of the last against which the shoe bottoming materials outside the inseam 18 are pressed and by reason of which the leveling pressure, which is applied perpendicularly to the plane of the shoe bottom, is given an inwardly directed component which causes the inseam to be displaced inwardly of the shoe, with a consequent tendency to tighten the lasted upper over the last and to close the welt crease 28.

The groove 14 may, as illustrated in FIG. 4, extend along the shank as well as about the forepart, the groove in that case extending about the peripheral margin of the last bottom from breast line to breast line. The inner edge of the groove 14 merges into the central cambered surface of the last bottom without any perceptible line of demarcation. The application of an obliquely arranged leveling instrument 32 to the shank portion of a shoe on the last illustrated in FIG. 4 will, by its pressure applied downwardly to the margin of the sole, not only close the welt crease but will, by reason of the grooved surface of the last, tend to force the inseam inwardly. At the same time, the groove relieves the pressure upon the inseam so that the inseam does not offer objectionable resistance to the action of the roll.

Under some conditions, however, it is desirable to have the groove extend about the forepart only and at the shank to provide a recess 34 with outer walls 36 extending heightwise of the last, the recess extending entirely across the shank portion of the last and having a width sufficient to receive the shank portion of the insole, as illustrated in FIGS. 1 and 3. The depth of the recess 34 may be equal to the thickness of the insole or may be less than or greater than the in-

sole thickness. This form of the shank portion of the last enables the leveling pressure to be applied to the outsole, welt and upper between the leveling instrument and the rigid surface of the last outside the recessed portion of the shank. Thus, the last provides a firmer support for the upper than is afforded by the margin of the insole against which the leveling pressure would be applied if the last were of the usual construction. The result is a close shank which will remain close during the wear of the shoe.

The last described above is not claimed herein since it is claimed in my copending application Serial Number 211,823, filed Aug. 9, 1927 of which this application is a division.

The method of leveling a shoe on the illustrated last preferably consists in supporting the extreme edge portion of the insole, which is effected by the edge 16 of the last bottom, relieving opposition to the pressure on the inseam, which is effected by the shallow groove 14, and applying pressure progressively about the periphery of the outsole to force the margin of the outsole and welt against the supported edge of the insole, which operation is performed, for example, by the relative traverse of the shoe and a leveling instrument, such as a roll, longitudinally of the shoe bottom while applying pressure heightwise of the last. In this method the inward and heightwise inclination of the margin of the last bottom formed by the outer portion of the groove 14 is utilized to cause the leveling pressure to force inwardly the inseam and consequently to tighten the upper and close the welt crease.

A shoe leveled by the present method, when removed from the last, has a substantially flat interior surface on the insole. The groove 14 forms no appreciable ridge on the inner surface of the insole and is of barely sufficient prominence to be evident to the sight or to the touch. The outwardly curved portion of the margin of the insole is outside the area of contact of the foot with the insole, and this formation of the margin tends materially to prevent the margin of the insole from curling upwardly and causing discomfort to the foot, as it occasionally does in welt shoes made on the usual last.

Having thus described by invention, what I claim as new and desire to secure by Letters Patent of the United States is:

1. That improvement in methods of leveling shoes which consists in applying leveling pressure to the marginal portion of a shoe sole which is secured to the upper of the shoe by a line of fastenings while supporting said portion of the sole by means having an inclined surface, thereby causing the leveling pressure to force the said line

of fastenings inwardly away from the edge of the sole.

2. That improvement in methods of leveling shoes which consists in supporting the 5 insole of a welt shoe adjacent to its marginal edges, applying pressure to the marginal portion of the outsole, and directing said pressure by means having an inclined surface to cause the leveling pressure to force the 10 inseam inwardly of the shoe.

3. That improvement in methods of leveling welt shoes which consists in supporting the feather of the insole, progressively applying pressure about the periphery of the 15 outsole to force the welt and upper together, and relieving pressure on the inseam to prevent interference of the seam with the leveling operation.

4. That improvement in methods of leveling 20 shoes which consists in applying pressure to the margin of the outsole while utilizing a last having along the margin of its bottom face an inwardly and downwardly directed surface to cause the leveling pressure to force the inseam inwardly of the shoe.

In testimony whereof I have signed my name to this specification.

CLARENCE I. LANDER.

CERTIFICATE OF CORRECTION.

Patent No. 1,784,455.

Granted December 9, 1930, to

CLARENCE I. LANDER.

It is hereby certified that error appears in the printed specification of the above numbered patent requiring correction as follows: Page 1, line 81, strike out the words "of the shoe bottom because they are" and insert instead and toward the body of the last. This; and that the said Letters Patent should be read with this correction therein that the same may conform to the record of the case in the Patent Office.

Signed and sealed this 7th day of July, A. D. 1931.

M. J. Moore,
Acting Commissioner of Patents.
